partnership composed of George Codish, Jonas
A. Senter, and Max Potash

Application January 13, 1945, Serial No. 117,420

Term of patent 14 years

(Cl. D7—7)

To all whom it may concern:

Be it known that I, George Codish, a citizen of the United States, residing in New York city, county of Bronx, State of New York, have invented a new, original, and ornamental Design for a Woman's Shoe or the like, of which the following is a specification, reference being had to the accompanying drawing, forming a part thereof.

Fig. 1 is a side perspective view of a woman's shoe showing my new design;

Fig. 2 is a perspective view of the opposite side shown in Fig. 1; and

Fig. 3 is a rear perspective view.

I claim:

The ornamental design for a woman's shoe or
the like, as shown.

GEORGE CODISH.
